UNITED STATES PATENT OFFICE

2,468,319

POSTHOLE DIGGER ATTACHMENT

Harold B. Adams, Kansas City, Mo.

Application August 12, 1946, Serial No. 689,983

3 Claims. (Cl. 255—19)

1

This invention relates to improvements in post hole digger attachment for tractors and has particular reference to a rotary type earth drilling auger, and is an improvement over my pending application, Ser. No. 574,493, filed January 25, 1945.

The principal object of the present invention is the provision of an earth drilling auger attachment for tractors that will automatically take a vertical position regardless of the contour of the ground on which the tractor is positioned.

Another object of the invention is the provision of a post hole digging apparatus having a universally adjustable torque bar that eliminates substantially all twisting strains and binds and facilitates rapid digging.

Other objects are simplicity and sturdiness of construction, ease and accuracy of operation and adaptability for use on the various types of standard farm tractors.

With these objects in view, as well as other objects which will appear during the course of the specification, reference will be had to the drawings wherein:

Figure 1 is a side elevation of a post hole digger attachment for tractors embodying this invention.

Fig. 2 is a plan view of the digger shown in Figure 1.

Fig. 3 is an enlarged plan view of a portion of the digger.

Fig. 4 is an enlarged elevational view of an outer portion of the apparatus with parts shown in section.

Fig. 5 is a fragmentary sectional view taken on line V—V of Figure 3.

Referring more in detail to the parts, the numeral 10 designates a tractor, mounted on wheel 12 positioned on axle 14 which is mounted on a differential housing 16. Housing 16 has spaced apart disc side plates 18 which are secured to the tractor housing 20 by means of screws 22. A power take-off shaft 24 driven in the usual manner by the tractor power unit extends from the rear of the tractor housing and is adapted to be operatively connected to drive associated equipment such as the present post hole digger.

The post hole digger attachment includes a substantially V-shaped frame or boom 26 comprising two side bars 28 joined together at their outer and upper extremities by means of a cross bar or headerplate 30 which is welded or otherwise attached thereto.

The lower extremities of side bars 28 are spaced apart and interconnected by cross bar 34 and

2

securing bolts 36. A series of bolt holes 38 formed through cross bar 34 permit of suitable adjustment of booms having side bars of different spreads. Angled clips 40 secured at their one end by means of bolts 42 to cross bar 34 and at their other end to the differential housing 16 by means of screws 22 serve to support the inner end of the boom to the tractor. Brace bars 44 secured adjacent the outer extremities of side bars 28 respectively by bolts 46 and at their inner ends to the differential housing by means of screws 22 are disposed in angled relation to the side bars 28 to stabilize the boom and secure its outer end in fixed relation relative to the supporting tractor.

A windlass 47 comprising a drum 49 mounted on crank shaft 51 which in turn is rotatably mounted in bracket 53 attached to one of the side arms 28 by means of bolts 55. Drum 49 is provided with end flanges 57 and 59, and the outer flange 59 is ratchet toothed at 61 to engage a pawl 63 pivoted at 65 to bracket 53 to support the drilling mechanism in a raised position. It will be noted that the windlass is disposed off center to permit free movement of the drilling parts in their universal movement.

Extending horizontally and substantially perpendicular to the header plate 30 is a trunnion 62 which is rigidly carried by the boom.

A sheave housing 65 having spaced apart side walls 64, a top wall 66 and a lower cross bar 68 bored at 70 to receive the trunnion 62 is provided whereby the housing 65 is pivotally mounted.

The housing is held in position on the trunnion by cotter key 67. A sheave wheel 72 is rotatably mounted on a pin 74 carried by side walls 64. Pin 74 is disposed at substantially a right angle to trunnion 62 and extends outwardly beyond side walls 64 to engage openings formed through ears 76 fixed to sleeve 80 whereby these parts are pivotally joined together. Sleeve 80 is round in cross section and is adapted to receive a guide rod 82. Rod 82 extends downwardly below sleeve 80 and is adapted to fit into the upper plate 86 of transmission housing 88 to which it is securely attached by means of bolt 90. The lower plate 92 of housing 88 is secured to plate 86 by means of bolts 94.

An opening 96 bored through the hub of plate 92 is in axial alignment with guide rod 82 and is adapted to receive for rotation therein a stub shaft 98 to which is securely mounted an auger 100. The inwardly projecting hub 102 of plate 86 is bored at 104 to receive the upper end of

shaft 98 on which is fixedly mounted the beveled gear wheel 106. The lower plate 92 of housing 88 is bored at 108 to rotatably receive shaft 110 carrying beveled pinion 112 which intermeshes with beveled gear 106. A square drive shaft 114 interconnected to shaft 110 by means of a universal joint 116 extends through the squared portion 118 of the driving tube 120. This driving tube is connected with take-off shaft 24 by a universal joint 122. This mechanism is so constructed and operated as to drive the parts regardless of the vertical position of the gear housing 88 relative to the ground surface. Furthermore, the auger and associated parts may be universally tilted relative to the boom 26. A cable 128 attached by means of bolt 96 to the gear housing extends over sheave wheel 72 thence over drum 61 to which it is securely attached at its extremity. When the parts are in position, as shown, with the pawl 63 engaging ratchet teeth 61 the auger and associated parts will be maintained in the raised position. During the drilling operation as hereinafter described, the pawl 63 may be swung forwardly to disengage the ratchet teeth and the auger will be fed by gravity to contact the earth and then rotated by the powered tractor to bore the desired hole. It will be noted that the cable 128 is hitched to the gear housing at one side of the center thereof in order to support the driving rod and upper associated parts in such a way as to maintain the axis of the auger member in a substantially vertical position. The sheave wheel 72 is so positioned that the flanged edges thereof are spaced sufficiently close to the top wall 66 of the housing as to preclude any accidental dislodgment of the cable from the wheel. Since there is a tendency of the gear housing 88 to rotate during the drilling operation it has been found convenient to provide a torque bar 130 which is universally joined to one of the side bars 28 by a bracket 132 having an eye 134 which interconnects with an eye 136 formed integral with the inner end of the torque bar 130. This torque bar is of circular cross section and is slidably mounted in a sleeve 138 having a stub shaft 140 extending diagonally therefrom which is pivotally mounted in plate 142 attached to a gear housing 88 by means of bolts 94.

It will be noted that this torque bar extends forwardly through sleeve 138 a sufficient distance to serve as an operating handle 144 whereby the operator may force the auger more forcefully into the earth's structure during the digging operation and may also raise the auger if and when it is found necessary. Due to the mounting of the torque bar 130 as described, the twisting strains and binds of the operating parts is substantially eliminated and the torque bar adds much rigidity and strength to the entire machine.

What I claim as new and desire to cover by Letters Patent is:

1. A tractor attachment for boring substantially perpendicular holes into the earth regardless of out of level position of the tractor on which the attachment is adapted to be mounted including a boom, means for rigidly supporting the boom on a tractor to project outwardly therefrom, a pulley bracket, means pivotally mounting the pulley bracket on the boom for movement on a substantially horizontal axis, a guide, means for pivotally mounting the guide on the bracket for movement on a substantially horizontal axis transverse to and above the first named axis to cooperate with the first-named mounting means in maintaining perpendicularity of the guide, a

drive housing, an auger carried by and depending from the drive housing, a rigid member fixed to and extending upwardly from the drive housing for slidable support in the guide, a windlass having fixed support relative to the boom, a pulley rotatably carried on the pulley bracket, a flexible member operable on the pulley and having one end anchored with respect to the drive housing and having the other end connected with the windlass for raising and lowering the auger relatively to the guide, means in the driving housing having driving connection with the auger and adapted for connection with a power takeoff of the tractor to rotate the auger, and a torque member between the drive housing and boom for resisting rotation of the drive housing, said torque member having self-adjusting connections with the drive housing and said boom to cooperate with the guide in maintaining perpendicularity of the auger.

2. A tractor attachment for boring substantially perpendicular holes into the earth regardless of out of level position of the tractor on which the attachment is adapted to be mounted including a boom, means for rigidly supporting the boom on a tractor to project outwardly therefrom, a pulley bracket, means pivotally mounting the pulley bracket on the boom for movement on a substantially horizontal axis, a guide, means for pivotally mounting the guide on the bracket for movement on a substantially horizontal axis transverse to and vertically above the first named axis to cooperate with the first-named mounting means in maintaining perpendicularity of the guide, a drive housing, an auger carried by and depending from the drive housing, a rigid member fixed to and extending upwardly from the drive housing coaxially with said auger for slid-able support in the guide, a windlass having fixed support relative to the boom, a pulley rotatably carried on the pulley bracket coaxially with the pivotal axis of said guide, a flexible member operable on the pulley and having one end anchored with respect to the drive housing and having the other end connected with the windlass for raising and lowering the auger relatively to the guide, means in the drive housing having driving connection with the auger and adapted for connection with a power take off of the tractor to rotate the auger, and a torque member between the drive housing and boom for resisting rotation of the drive housing, said torque member having self-adjusting connections with the drive housing and said boom to cooperate with the guide in maintaining perpendicularity of the auger.

3. A tractor attachment for boring substantially perpendicular holes into the earth regardless of out of level position of the tractor on which the attachment is adapted to be mounted including a boom, means for rigidly supporting the boom on a tractor to project outwardly therefrom, a pulley bracket, means pivotally mounting the pulley bracket on the boom for movement on a substantially horizontal axis, a guide, means for pivotally mounting the guide on the bracket for movement on a substantially horizontal axis transverse to and vertically above the first named axis to cooperate with the first-named mounting means in maintaining perpendicularity of the guide, a drive housing, an auger carried by and depending from the drive housing, a rigid member fixed to and extending upwardly from the drive housing coaxially with said auger for slid-able support in the guide, a windlass having

fixed support relative to the boom, a pulley rotatably carried on the pulley bracket coaxially with the pivotal axis of said guide, a flexible member operable on the pulley and having one end anchored with respect to the drive housing and having the other end connected with the windlass for raising and lowering the auger relatively to the guide, means in the drive housing having driving connection with the auger and adapted for connection with a power takeoff of the tractor to rotate the auger, a torque member between the drive housing and boom for resisting rotation of the drive housing, a guide pivotally connected to said drive housing and slidably supporting said torque member, and a ring fixed to the opposite end of said torque member and adapted to engage loosely a ring fixed to said boom for universally connecting said torque member to said boom.
